UNITED STATES PATENT OFFICE.

GEORGE A. GLAHN, OF WALLINGFORD, CONNECTICUT, ASSIGNOR TO
THE ANDREW B. HENDRYX CO., OF NEW HAVEN, CONNECTICUT,
A CORPORATION.

DESIGN FOR A BASE FOR BIRD-CAGES.

SPECIFICATION forming part of Design No. 37,366, dated March 7, 1905.

Application filed January 30, 1905. Serial No. 243,425. Term of patent 14 years.

To all whom it may concern:

Be it known that I, GEORGE A. GLAHN, a citizen of the United States, residing at Wallingford, in the county of New Haven and State of Connecticut, have invented a new, original, and ornamental Design for a Base for a Bird-Cage; and I do hereby declare the accompanying drawings to be a full, clear, and exact illustration of the same, and which said drawings constitute part of this specification, and represent, in—

Figure 1, a top or plan view of a base for a bird-cage embodying my design; Fig. 2, a side or edge view thereof.

I claim—

The ornamental design for a base for a bird-cage as shown.

GEORGE A. GLAHN.
